UNITED STATES PATENT OFFICE.

ALBERT PAUL COCHRANE, OF BROOKLYN, NEW YORK, ASSIGNOR TO HERVEY, BARBER & MCKEE, OF NEW YORK, N. Y., A FIRM COMPOSED OF EVERETT P. HERVEY, ARTHUR WILLIAM BARBER, AND LANIER MCKEE.

CONTAINER.

1,277,864.

Specification of Letters Patent.

Patented Sept. 3, 1918.

Application filed March 21, 1917. Serial No. 156,246.

To all whom it may concern:

Be it known that I, ALBERT PAUL COCHRANE, a citizen of the United States, and a resident of the borough of Brooklyn, in the 5 county of Kings and city and State of New York, have invented a new and useful Container, of which the following is a specification.

This invention is an improvement in containers and corner-pieces, and its object is to 10 secure a particularly inexpensive yet efficient construction. The invention is susceptible of embodiment in the containers of my Reissue Patent No. 14,294 of May 1, 15 1917, which are built up of separate flanged wall or side sections united and stayed at the apical corners by pyramidal or virtually pyramidal clamping fasteners, the specific 20 departure in the present case being that the members of the fasteners are connected by a bending operation.

In the accompanying drawings:

Figure 1 is a perspective view of the container partly assembled; Fig. 2 is an inside 25 view of one of the corner fastenings; Fig. 3 is a section through the same and the walls of the box on the line 3-3 of Fig. 2, the condition illustrated being that which precedes the final crimping or uniting operation; Fig. 4 is a similar view showing the 30 members bent; Fig. 5 is an outside perspective view of a completed corner; Fig. 6 is an inside perspective view of a completed corner; Fig. 7 is a view like Fig. 4 illustrating 35 a modified construction; Fig. 8 is a similar view showing another modification; Fig. 9 is an enlarged cross-section on the line 9-9 40 of Fig. 8; Fig. 10 is a view similar to Fig. 4 showing another alternative construction; Fig. 11 is a section through the inner 45 member before assembling.

The container illustrated is a hollow parallelepiped built up of separate side or wall sections 1, 2, 3, 4, 5 and 6, preferably 50 of sheet metal and having inturned edge flanges 7. For purposes of distinction the sections may be referred to as end sections 1 and 2, side sections 3 and 4, bottom section 5, and top or cover section 6. The 55 flanges enable the sections to be mutually staying when fitted together in the erected condition and afford anchorage for the corner fastenings, as in my prior patent.

Each of the present corner fastenings,

shown in Figs. 3 and 4 for example, comprises inner and outer members 8 and 9, of substantially hollow pyramidal form, fitting the interior and exterior apical corners of the container. The inner member has a hollow protuberance 10 at the apex, and the cap has an apical recess, preferably formed by the interior of a larger hollow protuberance 11. In assembling, the protuberance 10 is inserted in the recess, and there locked by a suitable bending operation, which also 60 draws the two members of the fastening together tight against the walls between them. This can be effected by a tool which constricts the necks of both protuberances, leaving the fastener approximately in the condition shown in Fig. 4. These members are susceptible of economical manufacture from sheet metal, though obviously heavier metal and different manufacturing processes may 65 also be employed.

The extreme corners of the sections are provided with registering or complementary openings 12 for the passage of the protuberances 10. In one or more of the sections, particularly the cover section or the 80 one last applied in the closing of the box, the ends of the flanges may be separated by spaces or slots 13, which slide over the necks of said protuberances 10 of the inner corner members, which may thus be positioned before the cover is put on. During this operation and until locked the said members may be held in place by virtue of their protuberances being a somewhat tight fit in the corner openings of the end and side sections 90 1-4. Or, as shown in Fig. 8, the necks of these protuberances may be initially somewhat smaller than the heads, the latter being larger than the slots 13, which in such case should be provided in all the sections. 95 These slots and their co-operation with the fasteners are disclosed in a specifically different embodiment in my co-pending application Serial No. 156,245 filed March 21, 1917, wherein will be found claims generic 100 to the two applications.

Corner fastenings such as contemplated by this invention will usually have to be destroyed in order to open or disassemble the container, but can be replaced at slight expense if re-use of the container is intended. Thus, even though the fastenings themselves are not separable without injury, the box

sections are capable of being knocked down and nested compactly for return to the point of original shipment, where they may again be built up with new fastenings.

5 In the modification of Fig. 7 the protuberances 10^a and 11^a of the members 8^a and 9^a are open at the outer end, the inner protuberance being longer than the outer so that its edge may be bent back over the edge of the 10 outer protuberance after the manner of a tubular rivet, thus securing an especially tight clamping lock. Figs. 8 and 9 illustrate the fact that protuberances, such as shown in Figs. 3 and 4, may be united by 15 indenting them at spaced points instead of by an annular constriction.

Figs. 10 and 11 show a construction wherein the outer protuberance 11^b of member 9^b is hollow and open, while the inner protuberance 10^b of member 8^b is solid and provided with a terminal fin or flange 15 to be upset over the edge of the outer protuberance.

Various other modifications and alternative constructions may be devised. Attention may be called to the fact that the container sections may be provided with the outwardly offset seats for the fastening members shown in Figs. 12 and 13 of my application, Serial No. 156,245, filed March 21, 1917, above mentioned. It is to be understood that the term "container" is used generically and does not refer to particular use.

What I claim as new is:

35 1. A container constructed of separate wall or side sections united at the apical corners by fastenings comprising each a virtually pyramidal cap having an apical recess and a virtually pyramidal inner member having 40 an apical projection to enter said recess and adapted to be united with the outer member by bending.

2. A container constructed of separate wall or side sections united at the apical corners 45 by fastenings comprising inner and outer virtually pyramidal members formed respectively with diagonally projecting protuberances and sockets adapted to be locked together by a bending operation.

50 3. A corner-piece for containers comprising a virtually pyramidal cap having a recess at the apex, and a virtually hollow pyramidal inner member having a hollow protuberance entered in said recess and united 55 to the cap by bending.

4. In a container, a corner-piece comprising an angular outer member having a recess at the angle, and an inner member having a hollow protuberance held by bending in said recess. 60

5. In a container, a corner-piece comprising an angular outer member having an opening at the angle, and an inner member having a hollow protuberance passed through said opening and having its head larger than 65 the same so as to hold the members against separation.

6. A corner fastening for the apical corners of sectional containers, comprising a virtually pyramidal cap having a recess at 70 its apical region, a member adapted to engage the interior corner of the container, and a uniting element adapted to extend from the inner member through the apical corner 75 of the container into said recess in the cap and to be united with the cap by bending.

7. A corner fastening for the apical corners of sectional containers, comprising a virtually pyramidal cap having an opening through its apical region, a member adapted 80 to engage the interior corner of the container, and a uniting element adapted to extend from the inner member through the apical corner of the container and said opening in the cap and to be bent over on the 85 outside of the latter.

8. A corner-piece for containers comprising a virtually pyramidal cap having an apical recess, and a sheet metal inner member having a hollow protuberance adapted to 90 be received in said recess and locked therein by bending.

9. A corner-piece for containers comprising virtually pyramidal inner and outer sheet metal members having apical protuberances adapted to be received one in the other. 95

10. In a container or the like, the combination with sections meeting at an apical corner and there provided with an opening, 100 of a corner piece comprising a virtually pyramidal cap having an apical opening and an inner member having a protuberance adapted to be passed through the openings in the sections and in the cap, said protuberance having a constricted neck adapted to hold it in the opening of the sections while the corner piece is being assembled. 105

ALBERT PAUL COCHRANE.
